UNITED STATES PATENT OFFICE.

JAMES A. R. ELLIOTT, OF KANSAS CITY, MISSOURI.

ELECTRIC TRAP-RELEASE.

SPECIFICATION forming part of Letters Patent No. 558,051, dated April 14, 1896.

Application filed July 11, 1895. Serial No. 555,648. (No model.)

To all whom it may concern:

Be it known that I, JAMES A. R. ELLIOTT, of Kansas City, Jackson county, Missouri, have invented certain new and useful Improvements in Electric Trap-Releases, of which the following is a full, clear, and exact description, reference being had to the accompanying drawings, forming a part thereof.

My invention relates to trap springing or releasing devices, and more particularly to electrical trap-releases; and my object is to produce a device of this character which is more positive and reliable in action than any at present in use with which I am familiar.

15 A further object of the invention is to produce a device of this character which is simple, strong, durable, and inexpensive of construction.

To this end the invention consists in certain novel and peculiar features of construction and combinations of parts, as will be hereinafter described and claimed.

In order that the invention may be fully understood, I will proceed to describe it with reference to the accompanying drawings, in which—

Figure 1 shows a plan view of an inanimate-target trap and of an electrical release embodying my invention. Fig. 2 is a view on an enlarged scale, which illustrates the internal structure of the release.

In said drawings, 1 designates a rectangular box or casing, and 2 an electromagnet secured therein and having its terminals connected in the customary manner with the binding-posts 3, secured externally to the casing. 4 designates the armature of said magnet, which is pivoted, as shown at 5, close to one end, upon a boss in the interior of the casing, which armature is adapted to swing in the vertical plane of the poles of the electromagnet, being limited in its outward movement by the adjusting-screw 6, carried operatively by the casing. Said screw, after being adjusted to limit the swing or movement of the armature, may be reliably fixed at any point by the lock-nut 7. A further object of this lock-nut will be explained presently.

The armature is recessed at the side of the pivot opposite from the electromagnet, as shown at 8, and set in said recess is a tempered steel stop-plate 9, by means of the

screw-bolt 10, or it may be set detachable in any other suitable manner.

Pivoted to rotate in the vertical plane of 55 and above the armature at one side of the electromagnet, on the screw-bolt 11, is the disk 12, which projects through a slot in the upper side of the casing, and said disk is provided with a notch in its periphery to form 60 the opposite shoulders 13 14, which shoulders are adapted alternately to contact with the stop-pin 15, projecting internally of the casing into said notch. At a point nearly diametrically opposite to said notch is a second notch 65 16, which notch forms the comparatively high and low shoulders 17 and 18 at its opposite ends, and the base of said notch, when the disk is in its operative position, or, in other words, set to spring the trap, is parallel with 70 and slightly above the upper side of the casing.

Projecting from one side of the disk at a point near its periphery is a pin 19, and bearing against said pin is a spring 20, which is 75 secured by a screw-bolt 21 to a part of the casing. The tendency of this spring is to throw the disk, in the direction indicated by the arrow, to the position shown in dotted lines, Fig. 2. In its operative position, however, it 80 is retracted to the position shown in full lines, and holds the cylindrical tempered steel pin 21^a against the opposing end of the steel stop-plate 9, which thus prevents rotatable movement of the disk, said plate being held yieldingly by the weight of the armature into the path of said contact-pin, which, being cylindrical, provides the smallest reliable contact-surface which can be obtained, and therefore reduces friction between said pin and said 90 plate to the minimum. This is done to get a quick response of the disk when the armature is attracted to the electromagnet, as will be hereinafter referred to.

Projecting vertically from the upper side 95 of the casing is an arm 22, which is notched to form the overhanging shoulder 23, which shoulder projects outwardly some distance beyond the shoulder 17 of the disk when in its operative position. The casing is closed by 100 a detachable plate 24, and is mounted by means of any suitable bracket, such as shown at 25, upon the frame 26 of an inanimate-target trap, in this instance. The binding-posts

3 are connected by the wires 27 and 28 to an electrical battery, and located also in said circuit is a circuit maker and breaker, consisting of a simple contact push-button 29 or an equivalent device.

30 designates the swinging arm of the trap, which is approximately of inverted-T shape in cross-section, so that when said arm is grasped and moved into position to set the trap it first comes in contact with the shoulder 17 of the disk and moves the same from the position shown in dotted to the position shown in full lines, Fig. 2. This is done very quickly and carelessly, usually, and to prevent injury to the disk or any of its parts I provide the arm 22, having the shoulder 23, which takes off the impact of said arm from the disk.

When the trap is set, the pin 21^a, engaging 20 the stop-plate 9, prevents the outward movement of the arm 30, owing to the fact that in its path is interposed the short shoulder 18 of the disk, beyond which it cannot pass until the disk is moved without springing up over 25 it, and this it cannot do because of the overlapping shoulder 23, which prevents any upward movement or spring of said arm. This shoulder 23, in practice, will be found of great 30 advantage, owing to the fact that the arms 30 of traps of this type are frequently sprung, and therefore often accidentally ride over short or low obstructions and throw the target or release the bird before the proper time. With both shoulders, however, it is obvious 35 that said arm cannot move until the disk is operated. At the free end of the arm 30 a target-carrier 31, of the construction shown, or of any other suitable or preferred construction, is mounted.

40 The trap is sprung by simply pressing the push-button and completing the circuit to energize the electromagnet. Immediately this takes place the armature is attracted to the same and the contact-plate moves out of the path of the pin 21^a. The disk is then thrown 45 in the direction indicated by the arrow to the position shown in dotted lines, Fig. 2, by the action of the spring (not shown) on the arm 30, which throws the target. The disk is 50 retained in this position until the trap is reset by the attendant grasping the arm 30 and swinging it back to its former position. In accomplishing this it will be noticed that the arm passes the shoulder 18 and comes in contact with the shoulder 17, and thereby forces 55 the disk back to its original position, where its pin 21^a is immediately reengaged by the armature.

Owing to the fact that a quick response of 60 the disk to the action of the armature is es-

sential, it is obvious that the employment of a lock-nut is very important, as it prevents any accidental movement of the adjusting-screw 6, and therefore any increase of frictional surface by the plate 9 being projected 65 further into the path of the pin 21^a.

In case it is desirable to spring the trap without completing the circuit, I employ a sliding pin 32, which projects through an aperture in the bottom of the box. The upper end of said pin, or that within the box, is 70 diametrically enlarged, as shown at 33, so as to form a shoulder, which will prevent the pin from slipping through the aperture out of the casing.

When the trap is reset, the momentum given 75 the disk by the engagement of the arm 30 with the shoulder 17 would be apt to injure the spring 20 in a short time, and therefore the necessity of the shoulder 13 to engage the stop-pin will be apparent.

This release may also be used as conveniently to spring live-bird as "inanimate" traps by simply providing an arm 34, connected to the trap (not shown) with a slot 35, which will 80 engage the shoulder 18, as shown by dotted lines in Fig. 1.

Having thus described the invention, what I claim as new, and desire to secure by Letters Patent, is—

1. An electrical release for live-bird or inanimate-target traps, comprising a suitable casing, a notched disk rotatably mounted therein and projecting through a slot in said casing, a pin projecting from said disk, a stop-plate held yieldingly in the path of said pin, and an arm upon said casing, notched to form an overhanging shoulder which overlaps the notch in the disk, substantially as set forth.

2. An electrical release for live-bird or inanimate-target traps, comprising a suitable casing, an electromagnet therein, a circuit maker and breaker in the circuit with said magnet, a pivoted armature having a stop-plate at the end opposite to the magnet, an 100 adjusting-screw, a lock-nut thereon, a trip-pin for said armature, a spring-actuated rotary disk projecting through a slot in the casing and provided with a pair of notches, a pin engaging one of them and a trap-arm the 105 other, a shoulder overlapping said trap-arm, and a pin engaging the stop-plate, substantially as set forth.

In testimony whereof I affix my signature in presence of two witnesses.

JAMES A. R. ELLIOTT.
